US0D1063665S

(12) **United States Design Patent** (10) **Patent No.:** **US D1,063,665 S**
(45) **Date of Patent:** **** Feb. 25, 2025**

(54) **ELECTRONIC TAG**

(71) Applicant: **Samsung Electronics Co., Ltd.**, Suwon-si (KR)

(72) Inventor: **Goangtae Kim**, Suwon-si (KR)

(73) Assignee: **SAMSUNG ELECTRONICS CO., LTD.**, Gyeonggi-Do (KR)

(**) Term: **15 Years**

(21) Appl. No.: **29/905,247**

(22) Filed: **Oct. 18, 2023**

(30) **Foreign Application Priority Data**

Apr. 26, 2023 (KR) 30-2023-0016100

(51) **LOC (15) Cl.** **10-04**

(57) **CLAIM**

The ornamental design for an electronic tag, as shown and described.

DESCRIPTION

FIG. 1 is a front perspective view of an electronic tag, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depict portions of an electronic tag that form no part of the claimed design.

1 Claim, 6 Drawing Sheets
